UNITED STATES PATENT OFFICE.

VICTOR H. JENNINGS, OF WORCESTER, MASSACHUSETTS, ASSIGNOR TO MILLS WOVEN
CARTRIDGE BELT CO., OF WORCESTER, MASSACHUSETTS, A CORPORATION OF
MASSACHUSETTS.

CARTRIDGE-BELT.

1,015,801.

Specification of Letters Patent. Patented Jan. 30, 1912.

Application filed December 5, 1910. Serial No. 595,774.

To all whom it may concern:

Be it known that I, VICTOR H. JENNINGS, a subject of the King of Great Britain, residing at Worcester, in the county of Worcester and State of Massachusetts, have invented new and useful Improvements in Cartridge-Belts, of which the following is a specification.

This invention relates to improvements in cartridge belts, and particularly to a belt having pockets woven integral therewith and of greater longitudinal extent than the belt proper, and the object is to provide a belt of this character in which the pocket may be made to project any desired distance beyond the belt proper, and in which said pocket may be woven either with or without a partition or a reinforcement, and to provide a novel method of weaving such a belt by the exercise of which the belt may be rapidly woven, with all of the fabric in view of the weaver during the process of weaving.

With the above object in view, the invention consists in the novel features of construction hereinafter fully described, particularly pointed out in the claims, and clearly illustrated by the accompanying drawing, in which—

Figure 1 is a face view of a portion of a belt constructed in accordance with my invention; Fig. 2, a rear view of the same; Fig. 3, a similar view showing the floating threads before being cut off and the pocket finished; Fig. 4, a sectional view taken longitudinally through one of the pockets; Fig. 5, a transverse sectional view taken through the pocket, and Fig. 6, a similar view showing the pocket before cutting off the floating-threads and finishing.

Heretofore belts have been woven having a cartridge-pocket projecting below the lower selvage, reference being made to British Patent No. 7820 of 1908, granted to F. R. Batchelder. In the formation of such belt that portion of the pocket intended to depend below the belt is woven as a folded-up portion within that portion of the pocket corresponding in length to the width of the belt proper. This construction involves the weaving of additional picks for the folded-up plies and double the time necessary to weave a pocket. In addition, the weaver cannot see the folded-up plies while they are being woven nor regulate the size of the

pockets. Moreover, it is not practicable to produce a woven partition, or a reinforcement, and the pocket as finally woven and unfolded is more or less clumsy in appearance. Also in such belts as heretofore produced, the body portion of the belt can never be less than one-half the longitudinal extent of the pocket. By my improved method, the foregoing objections and restrictions are overcome.

To produce a belt in accordance with my invention, I draw in as many threads, suitably divided among the necessary number of harnesses, as are necessary to obtain when woven into cloth the greatest length of pocket, but so many of the threads as will make up the cloth forming that portion of the pocket depending below the belt proper, I carry in separate harnesses, so that they may be operated independently of the threads forming the belt proper. I begin by weaving as a solid fabric the necessary length of cloth to form the billet or plain portion of the belt, leaving out of action the harnesses carrying the threads beyond the width of the belt proper, these threads being carried through the loom as floaters. In the drawing, the numeral 1 designates the billet portion and 2 the floating threads. Having reached the point in the fabric where it is desired to form a pocket, I throw in the harnesses carrying the threads referred to as floaters, and pass the weft through all of the threads of the warp, forming the pocket 3 in the usual way, with the weft thread joining the upper and lower, or front and back fabrics at the bottom of the pocket. This gives a pocket, the front and back of which are integrally woven as a part of the belt, the upper portion also being bound into the belt, while the lower portion which projects below the belt is open at each side. Another length of plain belt is then woven, and then another pocket is formed as just described. Having woven as many pockets as may be desired and a sufficient length of plain web to complete the belt, the depending portions of the pockets are finished by cutting away the floating threads 2 and turning in the edges of the open sides of such depending portions so as to conceal the ends of the cut threads, and stitching the front and back walls together so as to close the pocket securely.

From the above-description, it will be seen that I can produce a belt of any width with an integrally-woven pocket of any longitudinal extent, the one not depending upon the other. For example, the belt might be only one inch in width and the pocket four inches in depth. It will also be seen that the fabric is at all times within sight of the weaver, and that the completed belt and pocket is neat and graceful in appearance.

Having thus fully described my invention, what I claim as new and desire to secure by Letters Patent of the United States, is:

1. The improved method of forming a belt having pockets of greater longitudinal extent than the width of the belt consisting in weaving the belt proper, the pocket-portions lying on the face thereof, and the front and rear walls of the projecting pocket-portion integral, carrying the threads forming said projecting-portions as float-

ing threads between the adjacent pockets, and subsequently cutting off said threads and uniting the walls of the projecting pocket-portions to form the complete pocket. 25

2. The improved method of weaving a belt having a pocket of greater longitudinal extent than the width of the belt proper, consisting in weaving that portion of the pocket lying on the face of the belt of certain of the threads used in weaving the belt proper, and weaving that portion of the pocket projecting beyond the belt of independent threads not employed in the weaving of the belt proper and pocket- 30 portion lying on the face thereof. 35

In testimony whereof I affix my signature in the presence of two witnesses.

VICTOR H. JENNINGS.
